TENNIS RACKET

William H. Schaefer and Richard E. Bender, San Diego,
Calif., assignors to General Dynamics Corporation, San
Diego, Calif.

Filed Feb. 16, 1973, Ser. No. 333,429

Term of patent 14 years

Int. Cl. D21—02

U.S. Cl. D34—5 ST

FIG. 1 is a perspective view of the tennis racket showing our new design;

FIG. 2 is a plan view of our tennis racket;

FIG. 3 is a section view through the racket frame, taken on line 3-3 in FIG. 2; and

FIG. 4 is a section view through the racket handle, taken on line 4-4 in FIG. 2.

The characteristic feature of our design resides in the concave curved inner surface of the racket frame in combination with the substantially uniform groove in the outer periphery of the racket frame, which groove further extends downwardly from the racket frame along the sides of the racket handle, as shown.

We claim:
The ornamental design for a tennis racket, as shown and described.
